CIRCULAR SPROUTER WITH A BOTTOM COVER

Harold Lavar Fox, 2823 Loran Heights Drive,
Salt Lake City, Utah 84109

Filed July 11, 1974, Ser. No. 487,454

Term of patent 14 years

Int. Cl. D11—02

U.S. Cl. D35—3 A

FIG. 10

FIG. 5

FIG. 6

FIG. 8

FIG. 7

FIG. 9

FIG. 1 is an exploded view showing my new design of a circular sprouter and its bottom cover looking angularly from the top-front;

FIG. 2 is a top plan view of the circular sprouter without its cover;

FIG. 3 is a bottom plan view of the circular sprouter without its cover;

FIG. 4 is a side elevational view of the circular sprouter including its bottom cover;

FIG. 5 is an enlarged top plan view of a section of the screen of the circular sprouter;

FIG. 6 is a top plan view of the sprouter's bottom cover;

FIG. 7 is a bottom plan view of the sprouter's cover;

FIG. 8 is a side cross-sectional view of the circular sprouter without its cover shown in FIG. 2 taken along line 8-8;

FIG. 9 is an enlarged cross-sectional view of the circular sprouter without its cover shown in FIG. 2 taken along line 9-9; and

FIG. 10 is a side cross-sectional view of the sprouter's bottom cover shown in FIG. 6 taken along line 10-10.

I claim:

The ornamental design for a circular sprouter with a bottom cover, as shown and described.
